TESTING DEVICE

Albert M. Rennau, Hannibal, Mo., assignor of
forty percent to Robert H. McKinney, Hanni-
bal, Mo.

Application August 6, 1935, Serial No. 34,964

5 Claims. (Cl. 175—183)

My invention relates to electric motors and generators, and has among its objects and advantages the provision of an improved testing device.

- 5 In the accompanying drawing:
Fig. 1 is a top plan view of the device;
Fig. 2 is a side elevation;
Fig. 3 is an enlarged sectional view along the line 3—3 of Fig. 2;
10 Fig. 4 is a view taken along the line 4—4 of Fig. 3;
Fig. 5 is a sectional view illustrating my extension feature; and
Fig. 6 is a perspective view illustrating the use
15 of the device for testing purposes.
- In the embodiment selected to illustrate my invention, I make use of a coil head 10 connected with an ampere-meter box 12 through the medium of a tubular member 14. Within the box 12 I mount an alternating current repulsion vane or direct current rectifier type ampere-meter 16. The ammeter 16 is electrically connected with a coil 18 in the head 10 through the medium of conductors housed within the tubular member 14.
- 20 In Fig. 3 the head 10 comprises a cap 20 having interfitting relation at 22 with the part 24. An opening 26 is provided in the cap 20 for the reception of the neck 28 of an iron pole piece or core 30. I rivet the neck 28 at 32 to fixedly connect the pole piece with the cap. The riveted end 32 embodies a curvature conforming to the cap 20 whereby the riveted end may be placed in contact with the laminations of the machine being tested.
- 25 Upon the pole piece I mount a fiber washer 34 adjacent the cap 20 and reduce the inner end of the pole piece at 36 for the reception of a fiber washer 38. Between the two washers and upon the pole piece 30 I wind a coil 40 of magnet wire, which coil is electrically connected with the two conductors 42 and 44 within the tubular member 14. I prefer to provide the pole piece 30 with a threaded bore 46 for the reception of a bolt 48 extending through an opening 50 in the part 24.
- 30 Thus the cap 20 may be drawn firmly into connected relation with the part 24 by tightening the bolt 48.

One end of the tubular member 14 is pressed onto a neck 52 cast integrally with the part 24. The coil head 10, the member 14, and the ammeter box 12 are preferably made of aluminum or other suitable material having non-magnetic properties.

Within the upper end of the member 14 I mount a tubular insert 54 having a closed end 56

provided with openings for the reception of spring contacts 58 and 60 connected with the conductors 42 and 44, respectively. The insert 54 is formed of insulating material. Grooves 62 and 64 are formed in the inner wall of the insert 54 for the reception of the contacts 58 and 60.

To the hollow neck 66 formed integrally with the ammeter box 12, I connect a plug 68 arranged to be inserted in the insert 54. The plug 68 comprises a brass sleeve 70 contained within an insulating sleeve 72 pressed into the neck 66. With the brass sleeve 70 I mount an insulating member 74 having a longitudinal bore for the reception of a conducting wire 76. I provide the member 74 with a shoulder 78 arranged to abut 15 the end of the brass sleeve 70.

A brass tip 80 is secured to one end of the wire 76 and abuts the end of the member 74. The opposite end of the wire 76 is electrically connected with a wire 82 electrically connected with 20 the ammeter 16 at 84. A second wire 86 electrically connected with the ammeter 16 at 88 is electrically connected with the brass sleeve 70 at 90. Because of the plug 68 the ammeter box 12 may be disconnected from the tubular member 14. With the parts arranged according to Fig. 3, the metallic tip 80 is positioned in electrical contact with the contact 58, while the brass sleeve 70 is in electrical contact with the contact 60.

I illustrate the ammeter 16 as being provided 30 with a flange 92 lying over the end 94 of the ammeter box. The end 94 may be provided with a plurality of threaded openings 96 for the reception of screws 98 passing through openings in the flange 92 for detachably securing the ammeter to the box.

In operation (see Fig. 6), my device is employed for testing electric motor and generator windings by disassembling the device being tested. This feature eliminates all danger of damaging 40 the machine being tested. For testing purposes the end 32 of the pole piece 30 is placed at the approximate center of the pole to be tested. Before the test is taken, the wires 100 and 102 of the winding being tested are electrically connected with conductors 104 and 106, respectively. I provide a variable resistance 108 having electrical connection with the separated ends of the conductor 104, and the latter and the conductor 106 are connected with a conventional plug 110 50 for connection with a conventional outlet for an alternating current supply.

With my invention the machine being tested receives its current from an alternating current source, which in most cases would be the same 55

current under which the machine operates in service. The variable resistance 108 is set for a suitable reading on the ammeter 16. All poles are tested in the same manner without changing the resistance 108. Thus by comparison of readings, shorted or reversed polarity turns can be easily recognized by variations in the ammeter reading.

In many cases it may be desirable to provide an extension for the tubular member 14 for increasing the distance between the ammeter and the coil head 10. My extension provides an accurate reading of the ammeter under all conditions of service. The accuracy of the instrument may be impaired when held in close proximity with powerful magnetic fields. The extension provides accommodation for variable conditions of operation, to the end that the instrument may be positioned at a sufficient distance from the mechanism being tested.

In Fig. 5 I provide a cap 112 of insulating material having a bore 114 for the reception of the plug 68. The cap 112 includes two spring contacts 116 and 118 of the same construction as the contacts 58 and 60. The wall of the bore 14 has frictional contact with the plug to hold the two parts in connected relation. I thread the neck 120 of the cap 112 for the reception of a protector 122 mounted thereon. This protector encloses the connections between the wires 124 and 126 and the contacts 116 and 118. The wires 124 and 126 are grouped as a cord 128, and the opposite ends of the wires 124 and 126 are electrically connected with a plug 130 of the same construction as the plug 68. I anchor the plug 130 in an insulating body 132 having threaded relation at 134 with a protective cap 136 of insulating material.

In making tests with the extension, the parts are arranged according to Fig. 5, and the plug 130 inserted in the insert 54 for establishing electrical contact between the plug 130 and the contacts 58 and 60. Otherwise the procedure for testing purposes is the same. The cord 128 may be of any desirable length.

I provide a testing device which is light in weight, whereby an ideal portable device is provided. The tester requires no outside field of excitation other than that of the motor being tested. My device is used for testing purposes, while the machine is not in operation, thereby eliminating the danger of damaging the machine. In addition the device may be used for testing reverse polarity of turns within a pole.

My device may be used for testing both the rotor and stator of a machine. The machine being tested receives its current from an alternating current source so that tests are made under current conditions commensurate with that under which the machine operates in service. A short will be more likely to appear with the machine tested under normal voltage.

Without further elaboration, the foregoing will so fully explain my invention that others may, by applying current knowledge, readily adapt the same for use under various conditions of service.

I claim:

1. A device of the type described comprising a hollow head, a pole piece mounted within the head and having a part extending to the exterior thereof and being adaptable to be positioned in

operating proximity with a machine part being tested, a coil wound upon said pole piece, an ammeter, a tubular member connecting the ammeter with said head, and electrical connections between the ammeter and said coil and being housed within the tubular member, said tubular member and said electrical connections being separable, and an extension for operatively connecting the separated tubular member including electrical connections connectible with said separated electrical connections.

2. A device of the type described comprising a hollow head, a pole piece mounted within the head and being arranged to be positioned in operating proximity with a device being tested, a coil carried by said pole piece, a tubular member connected with the head, an ammeter, a box for containing the ammeter and having a tubular extension, a plug positioned inside the tubular extension and being electrically connected with said ammeter, and electrical conductors mounted in said tubular member and operatively connected with said coil, said plug being insertable within the tubular member and having electrical contact with the conductors in the latter.

3. A device of the type described comprising a hollow head, a pole piece mounted within the head and being arranged to be positioned in operating proximity with a device being tested, a coil carried by said pole piece, a tubular member connected with the head, an ammeter, a box for containing the ammeter and having a tubular extension, a plug positioned inside the tubular extension and being electrically connected with said ammeter, electrical conductors mounted in said tubular member and operatively connected with said coil, said plug being insertable within the tubular member and having electrical contact with the conductors in the latter, said plug being removably retained within the tubular member, an extension comprising an insert plug shaped to be inserted in the tubular member, electrical conductors connected with said last-named plug, and a socket connected with said last-named electrical conductors, said socket being adapted to receive said first-named plug for establishing electrical connection between the latter and the last-named conductors.

4. In a testing device of the type described, a hollow head comprising two sections, a pole piece connected with one section, a screw connected with the other section and having threaded relation with the pole piece for connecting the two sections, said pole piece having a portion extending to the exterior of the head, to be positioned in operating proximity with a part to be tested, a coil mounted on said pole piece, an electrical measuring instrument, a support therefor, and an operating electrical connection between the coil and the electrical measuring instrument.

5. In a testing device of the type described, a head comprising two sections, a pole piece carried by one of said sections and having a portion positioned to be placed in operating proximity with a part being tested, connecting means between the other section and the pole piece for holding the two sections in connected relation, a coil carried by said pole piece, an electrical measuring instrument carried by said head, and an operating electrical connection between the coil and the electrical measuring instrument.

ALBERT M. RENNAU.
